UNITED STATES PATENT OFFICE.

FRANK A. OZEPECK, OF SEATTLE, WASHINGTON.

VALVE-GRINDER.

1,368,829.

Specification of Letters Patent. Patented Feb. 15, 1921.

Application filed March 29, 1920. Serial No. 369,479.

To all whom it may concern:

Be it known that I, FRANK A. OZEPECK, a citizen of the United States, residing at Seattle, in the county of King and State of Washington, have invented certain new and useful Improvements in Valve-Grinders, of which the following is a specification.

The objects of my invention are to provide a light-weight valve grinder, extremely simple in construction, equipped with adjustments for regulating the oscillation of the valve to be ground, and a bit adapted to engage valves of different forms. In this device, a simple adjustment will limit or extend the lateral movement of the valve for grinding. The bit is provided with a plurality of faces, and by the turn of a winged nut, the operator can present a valve-engaging portion for almost any kind of valve.

I attain these objects by the mechanism illustrated in the accompanying drawing, in which—

Figure 1 is a front elevation of the grinding tool.

Fig. 2 is a side elevation of said tool, with a section partly cut away showing a reduced end of the body, a ball bearing, and a tubular member extending over said portion of the body, and carrying at its free end an adjustable bit.

Fig. 3 is a view of the bit.

Fig. 4 is a detached view of a slotted crank arm, said arm being a part of the revolvable, bit-carrying portion of the device.

Referring to the drawings, 1 designates the body of the tool, carrying at one end the handle 2. The other end portion, as shown at 3, is reduced in diameter and squared off at its extreme end, adapting it to operate on a ball bearing. Rotatably mounted on the body is the gear wheel 4, and meshed therewith and similarly mounted is the smaller gear wheel 5, carrying the crank pin 6. 7 illustrates a connecting rod, provided at one end with a longitudinal slot 8, operating on said pin 6, the other end being rounded in form, as shown at 9. This rod is shown pivoted to the hub 10, at 11. Said rod is provided with the additional openings 12 and 13, adapted to

give pivotal connection thereto. The body of the tool has three complementary openings 14, 15 and 16, which permit the hub 10—which is bolted to the body—to be moved longitudinally into three different positions. Said openings in the rod accommodate it to the adjustment of the hub, thereby regulating the throw of the rod 17 and giving it adjustment for three different movements. 17 illustrates a spring riveted to the body, the function of which is to retain the member 18 on the body, and to permit its removal therefrom. Said member is tubular in its upper portion, and is adapted to revolve around the circumferentially reduced end of the body 3. It is provided with a circumferential groove 19 on its outer surface into which the free end 20 of the spring 17 fits, as retaining means. To remove the tubular member from the body the spring is simply lifted out of engagement with the groove. Fixedly attached to the member 18 is a laterally extending slotted crank arm 20, a detached embodiment of which is shown in Fig. 4. The slot is designated as 21, the rounded end of the rod 7 having a driving connection therein. At the lower end of the tubular portion of member 18, a seat 21' for a ball bearing 22 is provided. Extending from this seat to the free end of said member is a centrally located longitudinal slot 23 adapted to carry the bit shown in Fig. 3, and designated as 24. Said bit is held in the tool and adjustable to various positions through the instrumentality of the bolt and winged nut 25, operating through the opening 26 in the bit, and bores through the body. The crank and handle for actuating the mechanism are designated by figures 27 and 28 respectively.

By the mechanism, as illustrated, it is apparent that the rotation of the gears, cooperating with the rod 7 and its connections will impart an oscillating movement to the member 18 and the valve to be ground, connected with the bit. The operator can extend or limit the radius of action of the valve to be ground by the simple means heretofore described, by raising or lowering the block 15, and pivotally connecting the rod 7 through the proper

openings. A turn of the winged nut 25 will permit the bit to revolve on its bolt, and enable the operator to present the proper contact points for engaging the 5 valve.

I claim—

1. A device of the class described, comprising in combination, a body surmounted by a handle, the end of the body having a 10 circumferential reduced portion, carrying a revoluble tubular member provided with a ball bearing and a seat therefor, adapting said member to revolve around said portion, a circumferential groove and a 15 laterally extending slotted crank arm, adjacent its upper portion, its lower portion having a slot carrying an adjustable bit, rotatably connected with the body, a gear wheel carrying a crank arm and handle, 20 similarly mounted and meshed therewith, a smaller gear wheel carrying a crank pin, a connecting rod pivoted to the body, said rod carrying a slot in engagement with said pin, the other end of the rod having a ball 25 end in driving connection with the slot in the crank arm, a spring retainer connected with the body and in detachable

connection with the groove in said tubular member.

2. In a valve grinder, a combination comprising a body having at its lower end in revoluble engagement a member provided with a laterally extending slotted crank arm, located adjacent its upper portion, its lower portion carrying a bit, rotatably connected with the body, a gear wheel, similarly mounted and meshed therewith, a second gear wheel carrying a crank pin, a connecting rod pivoted to an adjustable hub on the body, said rod carrying at one 30 end a slot in engagement with said crank pin, the other end of the rod having a ball end in driving connection with the slot in the crank arm, the medial portion of said rod provided with a plurality of openings, 35 the body adjacent said hub provided with complementary openings, whereby the hub and rod may be adjusted to vary the travel of said rod, means for retaining or removing said revoluble member, and means for 40 manually holding and actuating the mechanism.

FRANK A. OZEPECK.
